UNITED STATES PATENT OFFICE.

WILLIAM T. ADAMS, OF READING, PENNSYLVANIA.

DOOR-BOLT.

SPECIFICATION forming part of Letters Patent No. 654,106, dated July 17, 1900.

Application filed April 21, 1900. Serial No. 13,747. (No model.)

To all whom it may concern:

Be it known that I, WILLIAM T. ADAMS, a citizen of the United States of America, and a resident of Reading, in the county of Berks 5 and State of Pennsylvania, have invented certain new and useful Improvements in Door-Bolts, of which the following is a specification.

My invention relates particularly to that class of door-bolts which is operated by means 10 of finger-levers designed to lie flush with the face of the door when the bolt is in either projected or retracted position.

The invention is fully described in connection with the accompanying drawings, and the 15 novel features are particularly pointed out in the claim.

Figure 1 is a front face view of a bolt embodying my improvements. Fig. 2 is a full rear view of the same. Fig. 3 is a side elevation, partly in section, the operating-lever being shown in its middle position. Fig. 4 is a similar view to Fig. 3, showing a slightly-modified construction.

A represents the bolt case or frame, which 25 comprises a front plate formed with a lever-slot a , terminating in finger-cupplings $a' a'$, and b is a bolt-operating lever which is pivotally mounted within the slot-recess and is provided with a rear arm or arms $b^3 b^3$, arranged to operate the slide-bolt plate C. This 30 bolt-plate, as shown, forms a movable bottom to the slot-recess a , in which the lever B is mounted, it being arranged to ride on the outer edges $a^3 a^3$ of parallel rear ribs or plates $a^2 a^2$ on the case-plate A, which ribs form the 35 side walls of the slot-recess a and are provided with bearing-openings $a^4 a^4$, in which the lever B is pivotally seated, as indicated, thus bringing the pivotal center of the latter 40 as close as possible to the case-plate A. The outer portion b' of the lever B is adapted to lie normally within the recess a either above or below the pivotal center b , with its outer or finger end b^2 extending into one or other 45 of the cupped recesses $a' a'$ in the case-plate. Within the latter the lever is provided, preferably, with two parallel inner arms $b^3 b^3$, lying outside of the vertical ribs or plates $a^2 a^2$ and having ends $b^4 b^4$, each of which is arranged, as shown, to bear against an ear c on 50 one side or other of the bolt-plate C, so as to

move the latter up or down with the corresponding movement of the lever-arms. A spring D, fixed to the bolt-plate, is arranged with its free end bearing upon the end of an 55 arm b^3 , so as to press the latter toward the inner face of the case-plate, thus normally forcing the outer portion b' of the lever into flush position in the recess a of the bolt-case, above or below the pivotal point b , except 60 when raised by the operator to either project or retract the bolt. As the spring D always moves with the bolt-plate in the same direction that the operating-arm b^3 of the lever swings, it is at all times bearing on said arm 65 at substantially the same distance from its fixed connection to the bolt-plate, thus avoiding any considerable wearing action and at the same time providing a practically-uniform tension upon the lever B.

The bolt-plate C moves in suitable guides 70 a^5 , provided at the rear of the case A, preferably on the outer edges of the vertical ribs or plates $a^2 a^2$, as shown, so as to form a movable rear wall of the recess a , the outer face of the 75 bolt-plate which is thus exposed being finished before assembling the parts.

The front or outside view of my bolt, as indicated in Fig. 1, shows merely the case-plate with recess a terminating in finger-cupplings 80 and bounded by entirely-closed side and rear walls having no unsightly dirt-catching openings and the outer portion b' of the lever lying flush in said recess. The pivoting-trunnions of the lever, fitted in the bearing-openings in 85 the side wall ribs or plates $a^2 a^2$, lie close to the rear wall of the case-plate, thus locating the pivotal center b as near to the latter as possible and permitting of the greatest possible swing of the inner lever-arms b^3 and resulting movement of the bolt-plate with comparatively-little cutting away of the door.

In Fig. 4 I have indicated a slightly-modified construction embodying my invention and adapted more particularly to provide for 95 a more extended movement of the bolt-plate C'. In this construction the inner arms of the lever instead of operating directly upon the bolt-plate are connected thereto by a link E, and the spring D', which is carried, as before, by the lock-plate, is arranged to bear 100 upon said link instead of upon the lever-arms

direct, thus requiring a reduced flexion of the spring. The operation is evidently substantially the same as previously described.

What I claim is—

- 5 The combination with the case comprising a plate having a longitudinal slot for the lever and longitudinal ribs or plates at the rear forming the side walls of a lever-recess, of a lever located in said recess and having trunnions pivotally mounted in said ribs and provided on their laterally-projecting ends at the rear of said plate with a bolt-operating arm
- 10

or arms lying parallel with and at the outer side of said ribs, and a sliding plate at the rear of said ribs arranged in engagement ¹⁵ with said operating arm or arms substantially as set forth.

Signed by me at Reading, Pennsylvania, this 18th day of April, 1900.

WILLIAM T. ADAMS.
